US0D1076892S

(12) **United States Design Patent** (10) **Patent No.:** **US D1,076,892 S**
(45) **Date of Patent:** **** May 27, 2025**

(54) **ANTENNA**

(71) Applicant: **KABUSHIKI KAISHA TOKAI RIKA DENKI SEISAKUSHO**, Aichi (JP)

(72) Inventors: **Koji Inafune**, Aichi (JP); **Kenichi Koga**, Aichi (JP); **Tatsuya Koike**, Aichi (JP); **Satoshi Mori**, Aichi (JP)

(73) Assignee: **KABUSHIKI KAISHA TOKAI RIKA DENKI**, Aichi (JP)

(**) Term: **15 Years**

(21) Appl. No.: **29/898,409**

(22) Filed: **Jul. 27, 2023**

(30) **Foreign Application Priority Data**

Assistant Examiner — Samina Vieth

(74) Attorney, Agent, or Firm — Greenblum & Bernstein, P.L.C.

(57) **CLAIM**

The ornamental design for an antenna as shown and described.

DESCRIPTION

FIG. 1 is a front perspective view of an antenna showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings are for the purpose of illustrating portions of the antenna that form no part of the claimed design.

The dot-dashed lines which define the bounds of the claimed design form no part of the claimed design.

1 Claim, 6 Drawing Sheets
